UNITED STATES PATENT OFFICE.

MARTIN J. LIDE, OF BIRMINGHAM, ALABAMA.

CONDENSER.

Application filed September 20, 1920. Serial No. 411,624.

To all whom it may concern:

Be it known that I, MARTIN J. LIDE, a citizen of the United States of America, residing at Birmingham, in the county of Jefferson and State of Alabama, have invented certain new and useful Improvements in Condensers, of which the following is a specification.

My invention relates to a steam condenser 10 of the counter-current type.

My condenser contemplates the introduction of the exhaust steam through a concentric bottom pipe which forms one of the principal supports for the condenser body 15 and opens upwardly thereinto near the bottom of the condenser body.

My invention further contemplates the provision of a hood or dome set over the top of the steam inlet pipe and having a marginal flange which depends below the top level of the steam pipe. In this way I obtain a uniform annular distribution of the entering steam and I cause it as it enters 20 to be directed downwardly and outwardly 25 towards the bottom of the condenser.

My invention further contemplates the utilization of the hood or dome as a wier from which the water overflows and falls in streams through the narrow marginal 30 passage in which the entering steam flows with a reverse bend before entering the main condensing space above the hood and completing its first pass.

My invention further contemplates the provision of an intermediate wier substantially spaced above and concentric with the hood wier and which is provided with bottom perforations which shower the water 35 throughout the main intermediate condensing space of the condenser body.

My invention further contemplates the utilization of water jets to scrub the steam twice as it enters and escapes from the intermediate condensing space, thereby making its second and third passes.

My invention also contemplates the provision of each wier with deep marginal vertical slots in its side wall which discharge the water in closely spaced sheets between 50 which the steam is scrubbed in each pass.

My invention also contemplates the provision of what I term a tripod support for the condenser, two supports being formed by the steam pipes and the other support being formed by the water pipe.

My invention also comprises the novel de-

tails of construction and arrangements of parts, which are all designed especially for simplicity and economy of construction, compactness in size and for the most effective and efficient utilization of the water to both scrub and spray the steam, the water having its flow broken up to the maximum possible extent for the length of its fall through the condenser body.

As illustrative of my invention, reference is made to the accompanying drawings, in which:

Fig. 1 shows the condenser in plan view; and

Fig. 2 shows the parts in side elevation.

Fig. 3 is an enlarged vertical section through the condenser body.

Fig. 4 is a half sectional view taken on the line 4-4 of Fig. 3.

Fig. 5 is a sectional view on the line 5-5 of Fig. 3.

Fig. 6 is a vertical cross sectional view of a modification of my invention.

Fig. 7 is a partial plan view of a modified type of a steam dome as viewed from the line 7-7 of Fig. 6.

Similar reference numerals refer to similar parts throughout the drawings.

As illustrated, the condenser body is formed of annular castings suitably connected, comprising a dome 1, a top ring 2, a lower ring 3 and a tapering bottom 4; which latter is flanged and attached to the vertical leg of the exhaust steam pipe 5. A pipe section 6, mounted within the bottom portion of the condenser and concentric with the pipe 5, forms a continuation thereof that extends to a point approximately midway of the lower section 3. The steam pipe 5 at its base connects by an elbow with a horizontal section 7 which in turn connects with an upright leg 8. At the base of its legs 5 and 8, the pipe carries integral bases 9 and 10 and these with the base 12 on the water inlet pipe 11 form the equivalent of a tripod support for the condenser body. The barometric tube 13 leads from a connection 14 provided at one side of the base 4. A branch pipe 15 from this barometric leg is connected to the casing 16 which has an overhead connection 17 to the dome 1 and a connection (not shown) to the exhaust pump, all as well understood in this art.

Above the top of the steam inlet pipe 6 I mount a hood comprising a marginal an-

nular flange 18 which extends below the top level of the pipe 6 and is supported by brackets 19. Integral with this flange is a dome which terminates in an inverted apex 5 20 depending concentrically above the pipe. Above the dome the flange walls are continued upwardly to form the wier wall 21 which is provided with an annular series of spaced vertically elongated narrow slots 22 10 which surround the wier and discharge the water in closely associated jets which leave between them narrow spaces for the flow of the steam. These jets flow downwardly through an annular passage 23 in which the 15 steam makes its reverse bend and passes upwardly above the hood. The steam gets a thorough scrubbing in its first pass through these water jets. The passage 23 is overhung by the flanged ring 24, the base of 20 which rests on the top of the lower body section 3 and has the vertical flange 24^a surrounding its inner edge forming with the middle section a wier from which water overflows onto the hood. This ring supports 25 the brackets 25 that are attached to the marginal wall of the wier 26 that is formed by a shallow pan, the bottom of which is covered with closely associated holes 27 through which part of the water entering the pan 30 is discharged in the form of a shower onto the top of the hood. The marginal wall of this wier is provided with closely associated vertically elongated slots 28 which discharge the surplus water in jets which are closely 35 spaced and adapted to repeat the scrubbing action obtained from the jets overflowing from the hood slots 22 and annular flange 24^a. The top section 2 is provided with an integral shoulder 29 which supports the upper wier 30, to which water is supplied by the pipe 11 and from which it overflows through the top annular series of elongated slots 31 which jet into the pan 26 and give the steam and gases a final scrubbing for 40 their last pass to the pipe 17.

In assembling my invention, the hood and pipe section 6 are lowered by means of a hook 32 onto the bottom section 4 and bolted thereto, and after the section 3 is bolted to 50 the bottom section 4, the ring 24 carrying the pan 26 is set on its flange and the upper section 2 is then bolted in place, after which the wier 30 is set in place and the top 1 bolted in position. The water and steam being admitted in ordinary course, the condensing operation is as follows:

The entering steam is spread by the point 20 of the dome and is discharged downwardly into the space 23 where it must make a reverse turn and pass upwardly through the jets of water escaping through the slots 22 of the hood wier. This constitutes the first 60 pass after which the uncondensed steam flows inwardly into the open and unobstructed space between the hood and the pan 65

26 which constitutes the main condensing space and is there acted upon first by the water jets from wier 24^a and then by the shower of water falling throughout the entire space through the holes 27. From this 70 space the steam, after making its second pass, flows outwardly and upwardly around the edge of the pan 26 and is there acted upon by the jets flowing through the slots 28, thus having its third pass and being 75 finally scrubbed for its last pass by the heavy jets discharged from the main wier slots 31.

My apparatus offers a maximum breaking up of the water and a minimum obstruction 80 to the flow of the steam while subjecting it to the action of the water so as to obtain a most efficient condensing action. The tripod support of the condenser, by means of its spaced bearings 9, 10 and 12, reduces 85 the cost of its base support to a minimum and affords great stability.

In Fig. 6 I show a modified type of my invention in which the brackets 32 on the steam inlet pipe support a curved dome 33 having radial ribs 34 which increase in thickness towards the base of the dome. The water in this construction enters through a port 35 and overflows from the top wier 36 onto the conical dome 37 from which it falls 90 onto a downwardly sloping shelf 38 that discharges it onto the top center of the dome 33. The steam makes the same number of passes as in Fig. 3 but the sheets of water offer greater resistance to it than the vertical jets and there is absent the shower arrangement which is effective between the second and third passes of the steam. The dome arrangement is most effective in the first pass 95 of the steam and the ribs 34 break up the 100 water so as to give it the effect of jets.

This invention is not intended to be restricted in scope to the specific embodiments shown, but contemplates such modifications as come within the spirit and scope of the 110 claims.

Having thus described my invention, what I claim as new and desire to secure by Letters Patent, is:—

1. In a steam condenser of the counter-current type, a cylindrical condenser body having a concentric steam inlet entering its bottom, a top wier having a water supply for marginal jet slots, a perforated spray pan disposed to receive the discharge from said slots and to discharge a shower through the central portion of the condenser body, a wier adapted to receive said shower and having a bottom forming a dome designed to divert the entering steam outwardly with a reverse flow inwardly into said shower space.

2. In a counter-current condenser, a body, a pipe to discharge steam upwardly into said body, a deflecting dome over said pipe

designed to produce a reversal of direction of flow of the steam, and means comprising a central shower pan and marginal wiers to direct spaced falling bodies of water 5 through the space above and surrounding the said dome.

3. A condenser of the character described, comprising a top wier having deep narrow marginal slots, a shallow pan disposed to receive the overflow from the upper wier and having its bottom provided with closely associated shower openings and also having marginal slots, an annular wier to receive the marginal jets overflowing from 10 said pan, a lower pan to receive the marginal overflow from the annular wier and the shower falling through the openings in the upper pan, a bottom pipe discharging the entering steam upwardly 15 against the lower pan, and depending marginal flanges on said pan which spread the entering steam into a downwardly and outwardly flowing annular sheet.

4. A condenser of the character described, comprising a top wier having deep narrow

marginal slots, a shallow pan disposed to receive the overflow jets from the upper wier and having its bottom provided with shower openings and also having marginal jet slots, an annular wier to receive the marginal jets overflowing from said pan and having marginal jet slots, a lower pan below said wier to receive the marginal overflow jets from the annular wier and also the shower falling through the openings in the upper pan, a bottom pipe discharging the entering steam upwardly against the lower pan, and depending marginal flanges on said pan which spread the entering steam into a downwardly and outwardly flowing annular sheet, there being in the marginal wall of the lower pan deep narrow vertical slots to jet the water in thin closely associated spaced sheets through the clearance between the depending marginal flange of the lower 30 pan and the condenser wall.

In testimony whereof I affix my signature.

MARTIN J. LIDE.
